(57) **CLAIM**

We claim the ornamental design for a handle for dental control head housing, as shown and described.

DESCRIPTION

FIG. 1 is a perspective view of a handle for dental control head housing.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof; and,

FIG. 7 is a bottom plan view thereof.

The even length broken lines and isolated, unshaded surfaces outside of the dash-dot boundary lines also form no part of the claimed design.
